(57) **CLAIM**

The ornamental design for a clamp, as shown and described.

DESCRIPTION

FIG. 1 is perspective view of a clamp showing my new design.

FIG. 2 is front elevational view thereof.

FIG. 3 is rear elevational view thereof.

FIG. 4 is left side elevational view thereof.

FIG. 5 is right side elevational view thereof.

FIG. 6 is a top plan view thereof; and,

FIG. 7 is a bottom plan view thereof.

The use of broken lines in the drawings illustrate environmental structure or boundaries that form no part of the claimed design.

1 Claim, 6 Drawing Sheets(56)
